Specification for Design.

Patented July 26, 1921.

Application filed November 20, 1920. Serial No. 425,566. Term of patent 3½ years.

To all whom it may concern:

Be it known that I, JULIUS SCHIRRA, a citizen of the United States, residing at Pittsburgh, in the county of Allegheny and State of Pennsylvania, have invented a new, original, and ornamental Design for a Music-Roll-Repair Device, of which the following is a specification, reference being had

to the accompanying drawing, forming part thereof.

The figure is a perspective view of a music roll repair device showing my new design.

I claim:

The ornamental design for a music roll repair device as shown.

JULIUS SCHIRRA.
